UNITED STATES PATENT OFFICE

AMOS S. VAN HISE, OF BROOKLYN, NEW YORK

DESIGN FOR A COMBINED FOUNTAIN PEN AND DESK STAND HOLDER THEREFOR

Application filed August 9, 1932. Serial No. 44,561. Term of patent 7 years.

To all whom it may concern:

Be it known that I, AMOS S. VAN HISE, a citizen of the United States, residing at Brooklyn, in the county of Kings, city of New York, and State of New York, have invented a new, original, and ornamental Design for a Combined Fountain Pen and Desk Stand Holder Therefor, of which the following is a specification, reference being had to the accompanying drawing, forming a part thereof.

The figure is a perspective view of a combined fountain pen and desk stand holder therefor showing my new design.

I claim:—

The ornamental design for a combined fountain pen and desk stand holder therefor substantially as shown.

AMOS S. VAN HISE.
